UNITED STATES PATENT OFFICE.

CHARLES H. SPANGLER, OF READING, PENNSYLVANIA, ASSIGNOR, BY DIRECT AND MESNE ASSIGNMENTS, TO METROPOLITAN EDISON COMPANY, OF READING, PENNSYLVANIA, A CORPORATION OF PENNSYLVANIA.

WATER-TREATING APPARATUS.

1,427,650.

Specification of Letters Patent. Patented Aug. 29, 1922.

Application filed August 24, 1920. Serial No. 405,637.

To all whom it may concern:

Be it known that I, CHARLES H. SPANGLER, a citizen of the United States, residing at Reading, in the county of Berks, and 5 State of Pennsylvania, have invented certain new and useful Improvements in Water-Treating Apparatus, of which the following is a specification.

My invention relates to water treating 10 apparatus adapted more particularly for softening or otherwise correcting the feed water supplied to boilers; the main purpose being to provide for reliably furnishing thereto a flow of determined chemical 15 liquid in quantity regulated in accord with the varying load on the plant served. The invention is fully described in connection with the accompanying drawing and is specifically defined in the claims.

Figure 1 of the drawing is a diagrammatic showing of a complete apparatus embodying the invention as it has been satisfactorily employed in actual practice; the specific construction and arrangement being 25 capable of modification without departing from the invention as hereinafter set forth. Fig. 2 is a separate view of the armature pawl.

As already stated my invention provides 30 for regulating the quantity of determined chemical liquid which is supplied to the boiler-feed water, in direct accord with the load on the station served; this method, which has not been heretofore employed so far as I am aware, not only permitting of 35 very convenient and satisfactory control of the chemical-liquid supply but also insuring more complete and reliable use of it for the intended purpose.

As indicated in the accompanying dia- 40 grammatic drawing, the required chemical liquid is stored in the tank 2 located above the point of its mixture with the boiler-feed water; which point may be a preheater such 45 as is commonly employed and indicated at

3. The chemical liquid is fed to the latter by gravity, through an adjustable discharge conduit 4 in the tank, as regulated by proper adjustment of the upper end 5 of said con- 50 duit relative to the surface of the stored liquid. The adjustment of this upper end 5 of conduit 4 to regulate the flow of chemical liquid is directly effected, as indicated, by the unwinding of a suspending cord 6

therefor, from a drum 7; as determined by 55 a regulating mechanism comprising an electro-magnet 10 and armature pawl 11, and an electro-magnet control mechanism comprising a rotary contact drum 15 and a relatively fixed contact arm 16; the frequency 60 with which the magnet is energized and the consequent rate of delivery from tank 4 being varied as desired by setting said fixed contact arm 16 to one or another cooperative position corresponding with the chang- 65 ing load on the station and indicated on a scale bar 17.

As diagrammatically indicated, the armature pawl 11 controls the unwinding of the conduit-suspending cord 6 from drum 70 7, through an ordinary train of gears; each energizing of the electro-magnet 10 causing a single tooth movement of gear 20 and a determinedly-reduced turning movement of drum 7 to lower the conduit end 5. The 75 frequency with which the electro-magnet 10 is energized is determined by the varying number of contacts made in a given time between the electrically connected contact-points 25 on contact drum 15 and the relatively fixed contact point on the adjustable arm 16; which variation is effected as fol- 80 lows: The contact drum 15 is rotated at a uniform speed, by a suitably connected motor 26 as indicated. The contacts 25 on said 85 drum are arranged in different circular series 27, 28, 29, &c. with a gradually increasing number in each series; so that the setting of the relatively-fixed contact arm 16 into cooperation with one or another of 90 said series will correspondingly vary the number of contacts made per revolution of the drum 15. This setting of the adjust- 95 able arm 16 is made to correspond with the load on the plant served, most simply by the action of the operator as in the showing indicated though it may obviously be effected automatically in well known manner when desired.

The feeding of the chemical liquid being 100 thus controlled by the varying number of contacts made at each revolution of the drum 15, it is important that the operator be constantly informed as to their effective work- 105 ing, and I therefore introduce into the electric circuit a contact-signal as indicated by lamp 30, the regular flashing of which will show that the energizing of the electro-mag-

net 10 and the resulting lowering of the conduit end 5 is being properly effected. The diagrammatic showing sufficiently indicates the general features and cooperative arrangement of the several parts of my apparatus to enable effective use thereof by those expert in the art in specifically modified form within the scope of my invention as defined in the claims.

10. What I claim is:

1. In an apparatus for treating boiler-feed water, a chemical liquid reservoir having an adjustable delivery conduit; means for adjusting said conduit comprising an electromagnet; and an electromagnetic circuit closing mechanism comprising relatively adjustable contacts.
2. In an apparatus for treating boiler-feed water, a chemical liquid reservoir having an adjustable delivery conduit; means for adjusting said conduit comprising an electromagnet and a pawl armature; and an electromagnetic circuit-closing mechanism comprising a rotary drum provided

with contacts arranged in circular series 25 of varying numbers and an adjustably-fixed cooperating contact.

3. In an apparatus for treating boiler-feed water, a chemical liquid reservoir having an adjustable delivery conduit; means 30 for adjusting said conduit comprising an electromagnet and a pawl armature; an electromagnetic circuit-closing mechanism comprising a rotary drum provided with contacts arranged in circular series of vary- 35 ing number and an adjustably fixed cooperating contact; and an interposed contact-signal device.

4. In an apparatus for treating boiler-feed water, a chemical liquid reservoir hav- 40 ing an adjustable delivery conduit; means for adjusting said conduit comprising an electromagnet; and an electromagnetic circuit closing mechanism comprising contacts arranged in series of varying numbers 45 and an adjustable cooperating contact.

In testimony whereof I affix my signature.
CHARLES H. SPANGLER.
